HUMIDIFIER

William Warren Cummings, Jr., Windermere,
Fla.

Application March 5, 1938, Serial No. 194,101

7 Claims. (Cl. 219—38)

This invention has for its object to provide a simple, compact, and efficient air conditioning or humidifying apparatus which can be readily installed in any desired location, which is of inconspicuous and pleasing appearance, and which, being automatic in its operation, and having once been installed and adjusted will effectively perform its intended function in a reliable manner with minimum attention.

10 My humidifier is characterized by the use of the drip principle of dripping water onto a hot head or heating element, within a superheated air chamber, where the water is instantly vaporized on contact with the hot head or heating element, instead or by flowing water onto a pan heated at a low temperature with slow evaporation, or of spraying water into the air. This drip principle has the advantage of eliminating odors of evaporating water or water drainage or water storage.

15 The high temperature of the head likewise prevents condensation of water from the air around the unit and prevents corrosion. The high temperature of the head also quickly replaces the heat lost through normal evaporation of water (about 20 1055 B. t. u. per pound of water evaporated), and insures a natural circulation of air through my device without mechanical aids such as a fan, insures rapid absorption of water into the air stream, and also insures a circulation of moist 25 air into the room. The temperature of the head or heating unit can be regulated and controlled to insure spontaneous vaporization of the water, and the water flow from the instrument can be likewise adjusted automatically. There is thus no 30 limit to the capacity of my unit.

The more particular objects of the invention, together with means whereby the latter may be carried into effect, will best be understood from the following description of an illustrative (and 40 at present preferred) embodiment thereof shown in the accompanying drawing, this, however, having been chosen for purposes of exemplification merely, it being obvious that the invention, as defined by the claims hereunto appended, may 45 be otherwise embodied without departure from the spirit and scope thereof.

In said drawing:

Fig. 1 is a side elevation and Fig. 2 a central vertical section of the complete device or apparatus.

50 Fig. 3 is a top plan view of the head.

Fig. 4 is a horizontal section taken substantially on the line 4—4, Fig. 1.

Fig. 5 is a wiring diagram.

The apparatus comprises a hollow supporting base 10 having air inlet openings 11 and from which rises a hollow upright or standard 12 communicating with the interior of the base and supporting at its upper end a hollow head 13 enclosing a chamber 14 which communicates at its lower

end with the interior of the standard 12 and at its top with the atmosphere through discharge openings 15. The head 13 is preferably provided with a heavy lining 16 of insulating material in order to prevent the relatively high temperatures, maintained as hereinafter explained within the chamber 14, from being communicated to the exterior of the head, the air discharge openings 15 passing through said lining.

Within the head 13 at the bottom of the chamber 14 is a hot head or electrical heating unit 17 of any suitable or well known type, having a head 18 of heat conducting material which is heated thereby. Electric current is supplied to the heater 17, through circuits hereinafter more fully described, by feed wires 19 which pass downwardly through the standard 12 and out through an opening in the base 10 to a source of electric current. It is to be understood that the electrical heating unit 17 may be replaced with a gas-heated or other heated element without departing from my invention.

Within the chamber 14, above the head 18 of the heating unit, is a drip head or nozzle 20 adapted to discharge water, preferably in drops, upon the heater head 18, said drip head being supplied with water through a pipe 21 which passes downwardly through the standard 12 to the base 10 where it is connected with a water supply, either by direct connection to a fixed supply pipe 22, as shown, or by means of a flexible hose or tube which may pass outwardly through the base in a manner similar to the wires 19 and be connected with a water supply pipe at any convenient place. The flow of water through the pipe 21 is controlled by a solenoid operated valve 23 of any suitable type in which energization of the solenoid acts to open the otherwise normally closed valve. Since such solenoid operated valves are well known, description thereof in detail is deemed unnecessary.

The electric circuit to the heater 17 and valve 23 is diagrammatically shown in Fig. 5. Said circuit includes two branches 24 and 25 both of which are controlled by a thermally operated, high limit switch 26 located in the chamber 14. Said switch 26 may be of any familiar type, biased to normally close the circuit but adapted to open the same when the temperature in the chamber 14 exceeds a predetermined limit, preferably about 500° F. The branch 24 includes the solenoid operated valve 23 and also includes a thermally operated low limit switch 27, likewise located in the chamber 14 and biased to normally hold the branch 24 of the circuit open but adapted to close the same when the temperature in the chamber 14 rises to a predetermined minimum, preferably about 230° F. The branch 25 includes the heater 17 and also includes a switch 28 controlled by a humidostat 29, preferably

located in the standard 12, and adapted to close the circuit to the heater when the relative humidity of the air within said standard falls below a predetermined amount and to open said circuit when the humidity exceeds a predetermined amount. Humidostats for thus controlling circuit closers are well known, and any suitable type, not requiring description in detail, can be employed. Said humidostat is preferably located opposite a transparent panel 30 in the standard 12, which panel may be opened in order to afford access to the humidostat for the purpose of setting or adjusting the same.

The parts being in the position shown in Fig. 5, with the switch 26 closed and the switches 27 and 28 open, the valve 23 is closed, and no current is supplied to the heater 17. Due to the free communication afforded through the inlet and discharge openings 11 and 15, the relative humidity 15 of the air in the hollow standard 12 will be substantially the same as that of the surrounding atmosphere. When this falls to a point determined by the setting of the humidostat 29, the latter will operate to cause the switch 28 to close 20 the circuit to the heater 17, which thereupon begins to heat the air in the chamber 14. Such heating of the air in said chamber tends to set up a thermo-siphonic circulation of air through the apparatus, air being drawn in through the 25 inlet openings 11, rising in the standard 12 to the chamber 14, and passing out through the discharge openings 15. When the temperature in the chamber 14 has risen to a point where water discharged upon the head 18 will be immediately vaporized and maintained in a vaporized condition, the switch 27 closes the circuit to the solenoid operated valve 23, thereby opening 30 said valve. Thereupon water from the head 29 will be dripped upon the head 18 of the heater 40 and be instantly vaporized in the superheated atmosphere of the chamber 14, the highly heated vaporized air passing out through the openings 15 to the atmosphere. When the humidity of the surrounding atmosphere has risen to the desired 45 point, the thus humidified air drawn in through the openings 11 and passing upwardly in the standard 19 will cause the humidostat 29 to operate the switch 28 to open the circuit to the heater 17, and the resulting fall in temperature 50 will cause the switch 27 to open the circuit to the valve 23, thereby permitting the latter to close. If, at any time during the operation of the device, the temperature in the chamber 14 should rise to a predetermined limit, the switch 26 will 55 open the circuit to both the heater 17 and valve 23, thereby discontinuing the heating action and closing the valve until the temperature has fallen to a safe level.

It is obvious, of course, that the shape and 60 form of my device may be changed without in any way departing from the spirit of my invention.

I claim:

1. An air conditioning apparatus comprising a 65 hollow base having an air inlet, a hollow standard communicating with said base, a hollow head providing a chamber communicating with said standard and having an air outlet, means for discharging water into said chamber, and means for vaporizing said water and heating said chamber.

2. An air conditioning apparatus comprising a 70 hollow base having an air inlet, a hollow standard

communicating with said base, a hollow head providing a chamber communicating with said standard and having an air outlet, a heating element in said chamber, and means for discharging water upon said element. 5

3. An air conditioning apparatus comprising a hollow base having an air inlet, a hollow standard 10 communicating with said base, a hollow head providing a chamber communicating with said standard and having an air outlet, an electric heating element in said chamber, a humidostat in said standard for controlling the current to said heating element, and means for discharging water upon said element.

4. An air conditioning apparatus comprising a 15 hollow base having an air inlet, a hollow standard communicating with said base, a hollow head providing a chamber communicating with said standard and having an air outlet, a heating element in said chamber, means for discharging water upon said element, an electrically controlled valve for controlling the discharge of said water, and a thermally controlled switch in said chamber for controlling the current to said valve. 20

5. An air conditioning apparatus comprising a 25 chamber, means whereby air may be admitted to and discharged from said chamber, an electric heating element in said chamber, a water supply pipe terminating in means for discharging water on said heating element, an electrically operated 30 valve in said pipe, an electric circuit comprising a branch including said heating element and a branch including said valve, a switch in said first named branch, a humidostat for controlling said switch and located to be influenced by air 35 entering said chamber, and a thermally controlled switch in said last named branch and located in said chamber.

6. An air conditioning apparatus comprising a 40 chamber, means whereby air may be admitted to and discharged from said chamber, an electric heating element in said chamber, a water supply pipe terminating in means for discharging water on said heating element, an electrically operated 45 valve in said pipe, an electric circuit comprising a branch including said heating element and a branch including said valve, a switch in said first named branch, a humidostat for controlling said switch and located to be influenced by air entering said chamber, a thermally controlled 50 switch controlling both of said branches and located in said chamber, and a thermally controlled switch in said last named branch and likewise located in said chamber.

7. An air conditioning apparatus comprising a 55 hollow base having an air inlet, a hollow standard communicating with said base, a hollow head providing a chamber communicating with said standard and having an air outlet, an electric heating element in said chamber, a water supply 60 pipe terminating in means for discharging water on said heating element, an electrically operated valve in said pipe, an electric circuit comprising a branch including said heating element and a branch including said valve, a switch in said 65 first named branch, a humidostat for controlling said switch and located in said standard, and a thermally controlled switch in said last named branch and located in said chamber.
